Primary Examiner — Cathron C Brooks(74) *Attorney, Agent, or Firm* — Mannava & Kang, P.C.;
Arash Behrvesh(57) **CLAIM**

What is claimed is the ornamental design for the body positioning support, as shown and described.

DESCRIPTION

FIG. 1 is a perspective view of a body positioning support; FIG. 2 is a front view of the body positioning support shown in FIG. 1;

FIG. 3 is a back view of the body positioning support shown in FIG. 1;

FIG. 4 is a right side view of the body positioning support shown in FIG. 1;

FIG. 5 is a left side view of the body positioning support shown in FIG. 1;

FIG. 6 is a bottom view of the the body positioning support shown in FIG. 1;

FIG. 7 is a top view of the body positioning support shown in FIG. 1;

FIG. 8 is a left side view of the body positioning support opened at approximately 90 degrees; and,

FIG. 9 is a left side view of the body positioning support opened at approximately 30 degrees.

The broken lines in the drawings illustrate environmental features and form no part of the claimed design.
